Primary Examiner — Christy Nemeth*Assistant Examiner* — Leah E Hoeferkamp(57) **CLAIM**

The ornamental design for a vehicle charging connector, as shown and described.

DESCRIPTION

FIG. 1 is a front perspective view of a vehicle charging connector showing the new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view.

The broken lines represent the portions of the design that form no part of the claim.

1 Claim, 8 Drawing Sheets(56)
